by *J. Roberto* Att'y.

UNITED STATES PATENT OFFICE.

HAROLD W. GOFF, OF NEW YORK, N. Y., ASSIGNOR TO WESTERN ELECTRIC COMPANY,
INCORPORATED, OF NEW YORK, N. Y., A CORPORATION OF NEW YORK.

ELECTROMAGNETIC DEVICE.

1,419,559.

Specification of Letters Patent. Patented June 13, 1922.

Application filed February 6, 1919. Serial No. 275,354.

To all whom it may concern:

Be it known that I, HAROLD W. GOFF, a citizen of the United States, residing at New York, in the county of New York and State 5 of New York, have invented certain new and useful Improvements in Electromagnetic Devices, of which the following is a full, clear, concise, and exact description.

This invention relates to electromagnetic 10 devices and more particularly to electromagnetic relays and step magnets.

The principal object of the present invention is to provide a simple and efficient electromagnetic device in which the same 15 energizing winding or windings serve to attract two armatures, one of which will be slow releasing. In accordance with this feature of the invention an electromagnetic device is provided having two armatures arranged in normally parallel magnetic 20 circuits, with an energizing winding or windings to effect attraction of both armatures arranged so that the field of force thereof traverses a portion of the normally parallel 25 magnetic circuits which is common to both armature circuits, and in which a short-circuited winding is arranged about a portion of the magnetic circuit of and individual to one of the armatures to render such armature 30 slow to release.

Another object of the invention is to provide an electromagnetic device having an armature, the release of which, upon the interruption or predetermined diminution of 35 the current through the attracting winding, will be accelerated by flux developed incidental to such interruption or diminution. In accordance with this feature of the invention, an electromagnetic device, having 40 an armature and an energizing winding or windings to effect attraction of the armature, is provided with a short-circuited secondary winding arranged about a magnetic circuit in parallel with the normal magnetic 45 circuit of the armature, in which the secondary winding develops flux incidental to interruption or diminution of the current through the attracting winding or windings, having a direction, within the portion of the 50 normal magnetic circuit of and including the armature, opposite to that of the flux residual in such normal magnetic circuit upon such interruption or diminution of current; whereby said armature is accelerated 55 in its release.

A further object of the present invention is to provide an electromagnetic device having two armatures and an energizing winding or windings to effect attraction of both armatures, the release of one of which is made slow by suitable means, and the release of the other of which is accelerated upon interruption or predetermined diminution of the current through the attracting winding or windings by the operation of the same means 60 by which the first armature is made slow releasing. In accordance with this feature of the invention, an electromagnetic device is provided having a pair of armatures arranged in normally parallel magnetic 65 circuits, with an energizing winding or windings to effect attraction of both armatures arranged so that the field of force thereof traverses a portion of the normal magnetic 70 circuits common to both armatures, and having one armature made slow to release by a short-circuited secondary winding arranged about a portion of its magnetic circuit, normally individual thereto; the flux developed 75 by the secondary winding; upon interruption or predetermined diminution of the current through the attracting winding or windings having a direction, within the portion of the normal magnetic circuit of and including the other armature, opposite to the 80 direction of the flux residual in the normal circuit of such other armature upon such interruption or predetermined diminution of current, to accelerate the release of such other armature. 85

Still another object of the invention is to provide an electromagnetic device, having two armatures, in which the same energizing winding or windings serve to attract two armatures, the normal magnetic circuits of which have a portion in common, and in which flux, developed incidental to the interruption or diminution of the current through the attracting winding or windings, will be of the same direction, within 90 the magnetic circuit of one of the armatures and the portion of the magnetic circuits common to both armatures, as the direction of the flux developed in the magnetic circuit of the one armature and the portion of such 95 magnetic circuits common to both armatures by the attracting winding or windings, in order to make the one armature slow to release. In accordance with this feature of the invention an electromagnetic device is 100 105 110

provided with two armatures arranged in parallel magnetic circuits, with an energizing winding or windings to effect attraction of both armatures so positioned that the field 5 of force thereof traverses a portion of the magnetic circuits which is common to both armatures, and in which a short-circuited secondary winding is arranged about a portion of the magnetic circuit of one armature 10 which is normally individual thereto, and in which the flux developed by the secondary winding, upon interruption or diminution of the current through the attracting winding or windings, is of the same direction, within the magnetic circuit of its armature and the portion of the magnetic circuits common to both armatures, as the direction of the flux developed in the magnetic circuit of the one armature and the portion 15 of the magnetic circuits common to both armatures by the attracting winding or windings; whereby such armature is made slow to release.

In the drawings Fig. 1 is a side view of 25 a slow acting relay embodying the invention.

Fig. 2 is a view of the armature end.

Fig. 3 is a view of an armature provided with a short circuited winding.

30 In the drawing the frame 30 of magnetic material has a pair of cores 31 and 32 of magnetic material secured to the base thereof. Energizing windings 33 and 34 surround the respective cores and are connected 35 so that the upper ends of the cores 31 and 32 when magnetized will be of opposite magnetic polarity. An armature 35 of magnetic material overlies the cores 31 and 32 and has a pair of upwardly bent 40 extensions 36 and 37 through which a pin 38 preferably of non-magnetic material extends. This pin also extends through inwardly bent lugs 39 and 40, carried by the frame 30, thus pivotally securing the armature 35 to the frame 30, and washers 41 of non-magnetic material are preferably provided between the extensions 36 and 37 and the respective lugs 39 and 40 to reduce the magnetic leakage between the armature 35 45 and the upwardly extending portion 42 of the frame 30. An upstanding lug 43 is provided on the armature 35 and a spring 44 secured between this lug and the portion 42 of the frame 30 normally holds this armature in its retracted position. An overlying portion 45 of the frame 30 carries an adjusting screw 46 by which the air gap between 50 the cores 31 and 32 and the armature 35 can be regulated. The armature 45 also 55 carries an arm 47 which can be used to impart movement to a variety of other apparatus. As shown, the arm 47 has a block of insulation 48 secured to the outer end thereof, which engages a spring contact 49. 60 Upon attraction of the armature 35 the con-

tact 49 engages a contact 50 and serves to control an electric circuit extending through these contacts. The contacts 49 and 50 can be conveniently mounted upon an extension 51 of the frame 30.

70 A second armature 52 as shown in detail in Fig. 3 is also carried by the frame 30, a non-magnetic pin 53 extending through lugs 54 and 55 of the frame 30 and extensions 56 on the armature 52, providing a pivotal 75 mounting for this armature. Non-magnetic washers 57 are arranged between the lugs 54 and 55 and the extensions 56 to prevent leakage of magnetic flux between the armature 52 and the frame 30 so that the flux 80 in the second armature will traverse the connecting bar 58 between the legs 59 and 60 thereof. A short-circuited winding 61, preferably of copper, surrounds the bar 58 and is preferably cast thereon. The respective 85 upper ends 62 and 63 of the legs 59 and 60 respectively are bent at right angles to the main portion thereof and shaped at their outer ends to partially surround the respective cores 31 and 32. A pin 64 is 90 carried by each of the legs 59 and 60, and each pin extends through an opening 65 in the portion 42 of the frame 30; the openings 65 being of such a size that the pins 64 do not engage the walls thereof. A pair 95 of pins 66 are also carried by the frame 30, and a spring 67 extending between each pin 66 and its respective pin 64 normally maintains the armature 35 in its retracted position. An adjusting screw 68 mounted in 100 the portion 42 of the frame 30 serves to regulate the air gap between the ends 62 and 63 of the armature and the respective cores 31 and 32.

105 The end 63 of the armature supports an actuating arm 69, which can be used to impart movement to a variety of other apparatus. As shown a block of insulation 70 is mounted to the outer end of the arm 69, and engages a spring contact 71 designed 110 to engage another contact not visible in the drawings, similar to the contact 50. Upon the attraction of the armature 35, these contacts are engaged and serve to control an electric circuit extending therethrough. 115 These contacts are conveniently mounted upon an extension 72 of the frame 30, in the same way as the contacts 49 and 50 are mounted on the extension 51.

120 Upon the completion of an energizing circuit through the windings 33 and 34, a magnetic field is developed to effect the attraction of both armatures 35 and 52. The magnetic circuit for armature 35 extends from core 31, across armature 35 to core 32, thence through 125 core 32, and across base of frame 30 to core 31; while the magnetic circuit of armature 52 extends from core 31, to the end 62; leg 59, bar 58, leg 60 and end 63 of armature 52 to core 32; thence through core 32, and across 130

the base of the frame 30 to the core 31. The cores 31 and 32 and the base of the frame 30 are thus common to both magnetic circuits. The current induced in the secondary winding 61 upon any change in the magnetic flux in the armature 52 develops a magnetic field which always opposes any change in the existing field. Thus, upon the energization of the attracting windings 33 and 34, the winding 61 delays the building up of the flux in the armature 52 to the point at which it is drawn to the cores 31 and 32, and correspondingly delays the movement of the armature 52; the added inertia due to the mounting of the winding 61 upon the armature also cooperating with the opposing flux to render this armature slow operating. The direction of the magnetic flux developed by the secondary winding 61, while opposite in direction to that in the armature 52 due to energization of the attracting windings 33 and 34, is of less strength so that the flux developed by the secondary winding 61 at this time does not retard the attraction of armature 35.

Should the current through the attracting windings 33 and 34 be interrupted or diminished the strength of the magnetic field developed thereby is correspondingly decreased without however changing its direction. Under these conditions the current induced in the secondary winding 61 by the change develops a magnetic field in the armature 52 of the same direction within the magnetic circuit thereof as the field existing therein upon such interruption or diminution of current through the attracting windings 33 and 34. The strength of the flux residual in the magnetic circuit of armature 52 is augmented thereby, so that a longer interval occurs before the resultant flux is decreased to a point at which this armature is retracted, than would be the case were the secondary windings 61 omitted. The armature 52 is thereby rendered slow releasing, and it will be noted that the residual flux and that developed by the secondary winding is of the same direction within the magnetic circuit of this armature, thus materially increasing the retardation in the release thereof. The added inertia of the armature 35 due to the mounting of the winding 61 thereon, still further delays the return of the armature to its retracted position.

The residual flux in the normal magnetic circuit of armature 35 within the common portion of the magnetic circuits of the two armatures is of the same direction as that developed by the secondary winding 61, but the flux, residual in the magnetic circuit of armature 52 and that developed therein by the secondary winding 61, tending to flow through the armature 35 is of a direction opposite to the flux residual in armature 35. This produces a more rapid diminution of

the residual flux therein and permits the armature 35 to be retracted more quickly than would otherwise be the case.

In the operation of the electromagnetic device, upon initial energization of windings 33 and 34, both armatures are attracted and engage their respective contact members 49 and 71 to complete their circuits. Upon momentary interruption or predetermined diminution of the current in the windings 33 and 34, the armature 35 is quickly released thereby disengaging its respective contact members 49 and 50, while the armature 52 is maintained in its attracted position thereby maintaining contact member 71 and its associated member, not shown, in engagement for an appreciable interval. By controlling the intervals between the interruptions or predetermined diminutions, the armature 52 can be maintained in its attracted position during such interruptions or diminutions and the armature 35 alternately retracted and attracted in response thereto, while an interruption or diminution in excess of the determined interval would effect the release of both armatures. Such an arrangement is particularly applicable to automatic telephone systems and the movement of the armatures can be utilized to control a variety of apparatus other than the circuit closures, such as 49 and 50; being suitable, for example, to the operation of selector and sequence switches used in automatic telephony.

If desired the frame 30 may be of non-magnetic material in which case a bar of magnetic material would preferably be mounted upon the base of the frame 30 and the lower ends of the cores 31 and 32 secured thereto, in order to still maintain an efficient magnetic path between the lower end of the cores.

What is claimed is:

1. An electromagnet having a plurality of independently movable armatures, a common energizing winding for moving said armatures, means on one of said armatures for delaying the movement thereof and means for adjusting the travel of each armature independently of the other armatures.

2. An electromagnetic device comprising two mechanically independent armatures, two normally parallel magnetic circuits each including one of the armatures, a short-circuited winding about a portion of one of the armatures to render it slow-operating, and an energizing winding to effect the attraction of both armatures arranged so that the field of force thereof traverses a portion of the two magnetic circuits common to both.

3. An electromagnetic device comprising two mechanically independent armatures, two normally parallel magnetic circuits each including one of the armatures, a short-circuited winding about a portion of one of

the armatures to render it slow-releasing, and an energizing winding to effect the attraction of both armatures arranged so that the field of force thereof traverses a portion of the two magnetic circuits common to both.

4. An electromagnetic device comprising two mechanically independent armatures, two parallel magnetic circuits each including one of the armatures, a short-circuited winding about one of the armatures, and an energizing winding to effect the attraction of both of the armatures arranged so that the field of force thereof traverses a portion of the two magnetic circuits common to both.

5. An electromagnetic device comprising two mechanically independent armatures, two parallel magnetic circuits each including one of the armatures, a short-circuited winding about one of said armatures, and an energizing winding to effect the attraction of both of the armatures arranged so that the field of force thereof traverses a portion of the two magnetic circuits.

6. An electromagnetic device comprising an armature, a magnetic circuit including substantially the entire armature, a second magnetic circuit arranged about and including a portion of the first circuit therein, an armature for said second magnetic circuit mechanically independent of said first armature, a short-circuited winding arranged about a portion of the second armature, and an energizing winding to effect attraction of both armatures arranged so that the field of force thereof traverses a portion of the two magnetic circuits common to both; whereby the flux developed by the short-circuited winding incidental to interruption or diminution of the current in the energizing winding has a direction, within the portion of the magnetic circuit of and including the first armature, opposite to that of the flux residual therein upon such interruption or diminution, to accelerate the release of said first armature.

7. An electromagnetic device comprising two mechanically independent armatures, a magnetic circuit including one of the armatures in an individual portion thereof, a second magnetic circuit including the other armature and arranged about and including a portion of the first circuit therein, a short-circuited winding arranged about the second armature, and an energizing winding to effect attraction of both armatures arranged so that the field of force thereof traverses

a portion of the two magnetic circuits common to both; whereby the flux developed by the short-circuited winding incidental to interruption or diminution of the current in the energizing winding is of the same direction in the second circuit and the common portion of the two circuits as the flux residual therein, and of an opposite direction within the portion of the first circuit including its respective armature therein as the flux residual in such portion of the first circuit, to render the armature in the second circuit slow to release and to accelerate the release of the armature in the first circuit.

8. An electromagnetic device comprising two mechanically independent armatures, two parallel magnetic circuits each including one of the armatures in an individual portion thereof, a short-circuited winding arranged about one armature and an energizing winding to effect attraction of both armatures arranged so that the field of force therein traverses a portion of the two circuits common to both; whereby the flux developed by the short-circuited winding incidental to interruption or diminution of the current in the energizing winding has a direction, within a portion of the normal circuit of and including the other armature, opposite to the direction of the flux residual in the circuit of such other armature upon such interruption or diminution to accelerate the release of such other armature.

9. An electromagnetic device comprising two mechanically independent armatures, a magnetic circuit including one of the armatures, a second magnetic circuit including the other armature and arranged about and including a portion of the first circuit therein, a short-circuited winding about said second armature, and an energizing winding to effect attraction of both armatures arranged so that the field of force thereof traverses a portion of the two circuits common to both; whereby the flux developed by the short-circuited winding, incidental to the interruption or diminution of current in the energizing winding, is of the same direction within the entire portion of one of the magnetic circuits as the flux residual therein upon each interruption or diminution to render the armature included in such circuit slow to release.

In witness whereof, I hereunto subscribe my name this 31st day of January, A. D. 1919.

HAROLD W. GOFF.
